SKI-TOW GRIPPERS

Kasimir Maurice Bieber, 7097 De l'Epee Ave.,
Montreal 15, Quebec, Canada

Filed Aug. 4, 1958, Ser. No. 753,049

4 Claims. (Cl. 104—202)

The invention relates to ski-tow grippers, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a ski-tow gripper for use by skiers for manually gripping a ski-tow rope so that the skier may be pulled to the summit of a ski hill and thereby to ensure a tight gripping engagement with the moving rope and which can be easily detachably secured and removed from the rope; to avoid the use of the usual hand leverage to hooking devices which are connected to the rope in order that the transmission of the traction thereof will be conveyed to the skier by means of a cord attached to the skier's waist belt and which has been found inconvenient inasmuch as in the event of a too sudden start, the rope must generally be seized by the hands of the skier in the usual way before such devices can be applied and thereby causing wear and tear on the skier's gloves and also effecting delays in the hook on and off by the skier to the ski rope; to eliminate the use of devices of metal construction for connecting the ski-tow to the skier which through frictional engagement generally causes damage to the ski rope and thereby necessitating repairs to the ski-tow; to furnish a ski-tow gripper that can be detachably connected to the ski-tow by the skier without the necessity of the skier having his hands touching the rope and thereby enabling the traction for the skier to be converted from manual means to a belt cord very quickly after the skier has contacted the ski rope; and generally to provide a ski-tow gripper that will be formed of few and simple parts, easy to assemble and efficient for its purpose.

In the drawings:

Figure 1 is a plan view of the ski-tow gripper.

Figure 2 is an end of the ski-tow cable.

Figure 3 is a cross sectional view of the ski-tow cable gripper as taken along the line 3—3 of Figure 1.

Figure 4 is a perspective view of the gripper as manually applied to the movable rope of the ski-tow.

Like numerals of reference indicate corresponding parts in the various figures.

Referring to the drawings, the gripping member as indicated by the numeral 10 consists of a hand mat 11 formed of leather, plastic, or any other suitable pliable material capable of having frictional engagement surface for contact with the tow rope.

The hand mat is preferably formed of an endless strip of material which is so shaped and secured as to terminate along its longitudinal edges into loops 12 and 13 for the purpose of engagement with the handles 14 and 15 made of wood or other suitable material while the central portion of the mat is suitably secured together to form a flexibility of the mat which is utilized when

2

the handle are manually pressed towards one another, or released from one another for engagement and disengagement with the tow-rope. The loops of the hand mat may be secured to the handles, or frictionally engaged therewith in accordance as to whether it is desirable for the handles to be exchanged in the hand mat for left or right-handed persons, or if the grippers are to be specifically constructed for sale to right or left-handed persons.

- 10 The handles 14 and 15 extend for some distance beyond the forward openings of the loops 12 and 13 and are suitably rounded or bullet shaped at their ends. The handle 14 is of a longer length than the handle 15 and is provided with a longitudinal orifice 16 in which is introduced a spring member 17, having one end connected to the washer 18 or other suitable plate which is wider than the diameter of the orifice 16 and is adapted to be in contact with the outer end 19 of the handle 14. The other end of the spring member may be directly or 15 indirectly connected with a hook member 20 which projects outwardly from the other outer end 21 of the handle 14, although it must be understood that in place of a hook, a guide ring or a similar unit may be used. The shorter handle 15 has the cord 22 secured to one 20 end thereof which is adjacent to the hook end of the handle 14 and this cord is engaged with the hook or ring member and from there on is connected to the user's belt and is of a length just about equal to his reach when holding the device to the tow rope 23 with 25 an extended arm.

In the form herein described the device is intended for the more usual right-hand rope tows where the user rides on the right side of the rope. By interchanging the position of the two handles, the device is readily adapted 30 for use on left-hand tows where the skier rides on the left side of the rope.

In the use of the ski-tow gripper the skier grasps the device firmly with his right hand and places it on top of the moving rope, the handles flanking the rope on either side and the belt cord passing on top of the rope. The belt cord ensures at this stage that the device will not be carried away by the moving rope but will stay within the skier's reach. He then presses the two handles 40 together, thus causing the hand mat to encircle the rope with some pressure, and will begin moving uphill immediately through the traction effected by the manually operated gripper and the operated rope. The pressure and, therefore, the traction may be increased by assisting with the left hand in squeezing the handles together. 45

50 It may be seen that the handles produce some leverage effect in causing the hand mat to press on the rope from all directions, which leverage enhances the hand pressure.

At this stage, it is still the manual traction which is causing the skier to move. To cause the device to come 55 into full operation by means of belt cord traction, the skier now transfers his left hand to the rope behind him grasping it firmly and thus assuming the load by means of left hand pushing on his body ahead of it while turning the device with the relieved right hand nearly 60 half a turn clockwise about the axis of the tow rope, so that the right-hand rod will come to the left of both the rope and the left hand rod. This will cause the belt cord to fall into the space between the rope and the right hand rod.

65 As soon as this has occurred, the skier will relax his left hand hold on the rope, causing himself to slip back somewhat, thus tightening the belt cord, and at the same time removing the rear part of the device from the rope to the right, which will cause it to assume the 70 position shown in Figure 3.

As may be seen, the belt cord, having been pulled off its holder atop the left hand rod, has now nearly en-

circled the rope, and the skier's weight is causing it to exert a considerable pressure both directly and by pressing the rod upward against the rope in a partial tourniquet effect. The more fully the skier's weight is pulling against this loop, the tighter it will become, thus ensuring an efficient, non-slip traction.

When nearing the end of the tow line, the skier has only to transfer his weight again momentarily to his left hand, which rests on the rope behind him, move the device's rear end away from himself, which will cause the front end of the right hand rod, rounded for that purpose, to slip the loop, take the device off the rope and drop it on the near side of the rope, and leave the tow line in the usual way.

It will, of course, be understood that modifications and ramifications may be made to this device without departing from the essential features of this invention.

The embodiments of the invention in which an exclusive property or privilege is claimed are defined as follows:

1. A ski-tow gripper comprising a gripper formed of a flexible mat-like member having the outer longitudinal portions terminating in loops, handles introduced in said loops and forming the connecting means for engagement with an uphill moving rope of the ski-tow through manual pressure on the hand mat and a cord secured to one of the handles and directed by the other handle for engagement with the ski rope and having its other end suitably secured to the skier.

2. A ski-tow gripper comprising a gripper formed of a flexible mat-like member, said flexible mat having a central portion and outer longitudinal loops, handles introduced in the loops of said flexible mat, a cord having one end secured to one of the handles and connecting with the other handle for engagement with an uphill moving ski rope and having its other end suitably secured to the body of a skier, said cord and said handles

5

being manually controllable through the flexible mat.

3. A ski-tow gripper comprising a gripper formed of a flexible mat-like member, said flexible mat having a central portion and outer longitudinal loops, handles introduced in the loops of said flexible mat, a cord having one end secured to one of the handles and connecting with the other handle for engagement with an uphill moving ski rope and having its other end suitably secured to the body of a skier, one of the said handles being longer than the other handle and provided with a longitudinal orifice therethrough, a spring member located in the handle having the orifice and having one end connected to the cord and the other end of the spring being secured to the other end of the handle, said cord and said handles being manually controllable through the flexible mat.

4. A ski-tow gripper comprising a gripper formed of a flexible mat-like member, said flexible mat having a central portion and outer longitudinal loops, handles of different lengths inserted in the loops of said gripper, the longer handle being provided with a longitudinal orifice, a spring member located in the orifice of the longer handle and having one end connected to a hook member extending beyond the handle and the other end secured to a retaining member located exteriorly of the handle, a cord having one end secured to the smaller of the handles and engaging with the hook of the other handle, and having its free end secured to the body of the skier.
